UNITED STATES PATENT OFFICE.

ALBERT E. SEIBERT, OF TOPEKA, KANSAS.

EXTENSION-STEP FOR RAILWAY-CARS.

1,168,339.

Specification of Letters Patent. Patented Jan. 18, 1916.

Application filed March 4, 1915. Serial No. 12,621.

To all whom it may concern:

Be it known that I, ALBERT E. SEIBERT, a citizen of the United States, residing at Topeka, in the county of Shawnee and State of Kansas, have invented certain new and useful Improvements in Extension-Steps for Railway-Cars; and I do hereby declare the following to be a full, clear, and exact description of the invention, such as will enable others skilled in the art to which it appertains to make and use the same.

My invention relates to new and useful improvements in extension steps for railway cars and has for its object to provide a simple and effective device of this character which may be cheaply made and installed and will take up comparatively small space when in folded position so that the desired clearance of the steps relative to the road bed is provided.

Another object is to provide an extension step of the character described that is provided with novel means including an operating handle to move it into and out of position, said operating handle being so arranged that when the step is in operative position it is disposed above the floor of the platform of the car to which it is attached and in a position where it will be readily seen by the porter or some other member of the train crew, thus the operating handle acts as a signal and indicates that the step is extended and prevents the usual trap door found on car platforms from being closed before the step is in out of the way position.

Another object is to generally improve and simplify extension car steps of the character described so as to render them more practical, reliable and efficient in operation and commercially desirable.

The above and additional objects are accomplished by such means as are illustrated in the accompanying drawings, described in the following specification and then more particularly pointed out as claimed.

With reference to the drawings, wherein I have illustrated the preferred embodiment of my invention as it is reduced to practice, and throughout the several views of which similar reference numerals designate corresponding parts, Figure 1 is a transverse sectional view taken through a car platform showing the steps thereon in side elevation and the extension step in position. Fig. 2 is an enlarged detail front elevation of a part of the operating means for the step, and

Fig. 3 is a detail sectional view showing one of the stops or latches for holding the operating lever in its true position.

Referring to the drawings by characters 60 of reference the numeral 1 designates as an entirety a car platform having depending from which the usual stationary steps 2. An extension step 3 is pivoted, as at 4, to the outer edge of the lowermost of the stationary steps and is arranged to be swung inwardly so that the riser portion thereof engages the under face of the lowermost step, as shown in dotted lines in Fig. 1.

Pivoted to a suitable bearing 5 that is secured to the uppermost of the steps 2 is an operating lever 6 that is bent to form an eye or loop 7 at its upper end. The lower end of the lever 6 is provided with an aperture 7' which receives one end of a horizontal crank 75 shaft 8. A suitable key 9 is employed to rigidly secure the lever 6 to the crank shaft 8. Suitable bearings 10 carried by the uppermost steps of the stationary steps 2 support the crank shaft 8. A connecting 80 rod 11 is secured at one end by means of a coupling member 12, pivotally to the cranks and its other end is connected with a T coupling 13. Connected with the T coupling 13 and extending outwardly at right 85 angles to the rod 11 on opposite sides of the coupling 13 are pivot rods 14 and 15 that are journaled at their ends in suitable bearings 16 secured upon the lower parts of the extension step 3.

As a means for locking the operating lever 6 in its true position I provide catches mounted upon the car platform 1 and which are designated 17 and 18 respectively. Each of these catches comprises a block having 95 a beveled outer face and which is secured by suitable fastening elements 18^a to the platform. The lever 6 is arranged to ride over the bevel face of the catches and to engage behind the larger end thereof, as 100 clearly shown in Fig. 3.

In operation when it is desired to move the steps from out of the way position, as shown in dotted lines in Fig. 1, to extended position, as shown in Fig. 1, the lever 6 is 105 pulled outwardly from engagement with the catch 18 and upwardly into vertical position so that it extends upwardly from the floor of the platform 1. The upward pull communicated with the lever 6 causes the 110 shaft 8 to rock and force the steps 3 into extended position. When the steps 3 are in

extended position, the upper end of the lever 6 projects above the platform 1, and such as a means for indicating that the steps are in an extended position, whereby to obviate any liability of the trap door being closed before the steps have been drawn back into their out of the way position. The rods 14 and 15 are preferably removable and it will be readily seen that the device may be completely disassembled and packed into small space. The operating mechanism for the step is so arranged that the step may be moved easily into and out of position.

In practice, I have found that the form 15 of my invention, illustrated in the drawings and referred to in the above description, as the preferred embodiment, is the most efficient and practical; yet realizing that the conditions concurrent with the adoption of 20 my device will necessarily vary, I desire to emphasize the fact that various minor changes in detail of construction, proportion and arrangement of parts may be resorted to, when required, without sacrificing any of 25 the advantages of my invention, as set forth.

What I claim is:

1. The combination with a railway car 30 platform and set of stationary steps, of an extension step pivoted to the lowermost of the stationary steps and arranged to swing inwardly underneath the lowermost of the stationary steps when in out of the way position, a crank shaft journaled to the uppermost of the steps, a lever secured to one end of the crank shaft and extending above the car platform when the step is in extended position and arranged to be disposed beneath the platform when the step is in out of the 35 way position, means to hold the lever in its two positions, and means operatively connecting the crank shaft with the steps.

2. The combination with a railway car 40 platform and set of stationary steps, of an extension step pivoted to the lowermost of the stationary steps and arranged to swing outwardly under the lowermost of the sta- 45

tionary steps when in out of the way position, a crank shaft journaled to the uppermost of the steps, a lever secured to one end of the crank shaft and extending above the car platform when the step is in extended position and arranged to be disposed beneath the platform when the step is in out of the way position, means to hold the lever in its two 50 positions, and means operatively connecting the crank shaft with the steps consisting of a rod pivoted to said crank shaft and right angularly extending rods secured to the lower end of said rod and being pivoted to the extension step at the ends thereof.

3. The combination with the stationary steps of the railway tie and platform therefor, of an extension step pivoted to the 55 lowermost of the stationary steps and arranged to swing inwardly beneath and in engagement with the lowermost step of the stationary steps, a crank shaft journaled transversely to the uppermost of the steps, a 60 rod pivotally secured at one end to the crank shaft at a point approximately centrally of the same and extending downwardly toward the extension step, a T coupling secured to the lower end of said rod, right angularly 65 extending rods connected with the T coupling, bearings secured to the extension step adjacent the ends and upon the under face thereof and receiving the ends of said last named rods, a lever secured to one end of 70 said crank shaft and arranged to extend upwardly through the platform floor when the step is in extended position and to be disposed beneath the floor of the platform 75 when the step is in out of the way position, and means to hold the lever in its two positions.

In testimony whereof I affix my signature in presence of witnesses.

ALBERT E. SEIBERT.
